UNITED STATES PATENT OFFICE.

ROBERT G. CLARK, OF BROOKLYN, NEW YORK.

PLAITING-MACHINE.

1,265,708.

Specification of Letters Patent.

Patented May 7, 1918.

Application filed May 26, 1917. Serial No. 171,089.

To all whom it may concern:

Be it known that I, ROBERT G. CLARK, a citizen of the United States, residing in the borough of Brooklyn, county of Kings, and 5 State of New York, have invented a new and useful Improvement in Plaiting-Machines, of which the following is a description.

This invention relates to plaiting machines and has particular reference to machines for plaiting long lengths of wide, stiff materials such as curtain or screen fabrics and materials.

Among the objects of my invention may 15 be noted the following: to provide an apparatus by means of which wide, stiff materials adapted for curtains, shades, screens and similar uses may be uniformly plaited continuously from long lengths, rolls or 20 bolts of material; to provide a mechanism such as noted in the foregoing, which will simultaneously plait and feed the material through the machine continuously and uniformly; to provide a power-driven apparatus 25 with plaiting blades so mounted as to have movement relatively to, and independently of, the carriers for the blades during the process of plaiting the material; to provide an apparatus consisting of a plurality 30 of rotary carriers each supporting oscillatory plaiting blades adapted to interact to produce, during a continuous feed of the material, uniform, parallel plaits; to provide a plaiting apparatus with a pair of 35 rotary carriers each having independently movable, oscillatory plaiting blades capable of interacting so as to uniformly plait the material, and feed it to and from the plaiting position, without objectionable stress or 40 strain thereon; to provide a plaiting apparatus with a plurality of interacting plaiting blades having revolving motion as a 45 unit and independent oscillatory motion for feeding-in and plaiting purposes; to provide a plaiting apparatus with interacting plaiting blades adapted to crease the material at the fold lines and impose little or no pressure upon the material between such 50 lines; to provide a plaiting machine embodying a pair of plaiting rollers with means whereby sharp folds may be made in the material without crushing, breaking, or injuriously straining the material, regardless of the character of the latter; and to 55 provide details of construction, in a ma-

chine of the character noted in the foregoing, which render the machine simple, effective, positive in operation and cheap to manufacture.

With the above objects in view, and others 60 which will be detailed during the course of this description, my invention consists in the parts, features, elements and combinations thereof hereinafter described and claimed.

In order that my invention may be clearly 65 understood, I have provided drawings wherein:

Figure 1 is a front elevation of a plaiting machine or apparatus embodying my invention, parts being broken away to show details, and the view being broken transversely in order to admit the same within the bounds of the sheet;

Fig. 2 is an elevation of the drive side of the machine, parts being broken away to 75 show details;

Fig. 3 is a section on an enlarged scale, taken on the line 3—3 of Fig. 1, looking in the direction of the arrows.

Fig. 4 is an enlarged sectional view of a 80 detail substantially on the line 4—4, Fig. 1, looking in the direction of the arrows; and

Fig. 5 is an enlarged sectional detail substantially on the line 5—5 of Fig. 3, looking in the direction of the arrows. 85

While I have shown my invention embodied in a machine adapted particularly for plaiting curtain and screen materials, I desire it understood that the idea of means is not limited to such uses; but, may be embodied in a much smaller machine adapted to make much smaller plaits for various commercial purposes. In fact, the invention herein disclosed may be embodied in a machine of any predetermined size, according 90 to the purpose or ultimate use of the plaited material. 95

Referring to the drawings, the numeral 1 indicates the bed of the machine which may be set upon legs or supports 2, and 100 which has erected thereon uprights 3, bolted or otherwise suitably secured at their base 4 to the bed, as clearly shown in Fig. 1. The uprights 3 form the fixtures of journal bearings, the detachable members of which 105 are indicated at 5 bolted or otherwise suitably secured to the uprights 3, as shown in Figs. 1 and 2. The upper pair of bearings 5 are adjustable for the purpose and by means presently described. Tie or brace, 110

bars 6 connect the two uprights 3 and may be secured thereto in any manner found suitable or convenient. Guard-plates 7 and 8, at back and front, respectively, of the machine, are suitably connected to the tie-bars 6, which latter is supported by the cross-bars 6^a, and depend so as to shield the operator from the upper plaiting member or set, to prevent accident and also to prevent 10 implements from being accidentally engaged with the plaiting blades.

The bed of the machine is also provided at the drive end thereof with a pair of bearings 9 in which the driving-shaft 10 is journaled, which shaft has, at one end, the band or power-wheel 11, which may be referred to as the source of power, and at its other end a worm 12 meshing with the worm-wheel 13 fixed upon one end of the lower shaft 14, journaled in the lower pair of bearings 5 and having at its other end the gear-wheel 15, meshing with the gear-wheel 16, carried by one end of the upper shaft 17, journaled in the upper pair of adjustable bearings, said shafts 14 and 17 being the media for supporting and revolving the two sets of plaiting blades. The coöperating and interacting sets of plaiting blades, mounted upon the shafts 14 and 17, are identical and have identical movements and are operated by identical mechanisms. Consequently, a description of one set will suffice for the other, and like parts of the same will be indicated by similar reference characters.

Referring now to Figs. 4 and 5, it will be seen that the lower shaft 14 is journaled, at its opposite ends, in bushings 18, set within the opposite bearings 5—5^a, and that each bushing, adjacent the inner side of its bearing, has fixed thereon a cam 19 by means of a spot-screw 20, said stationary cam being, throughout the major portion of its circumference, concentric with the shaft 14, and, at a predetermined point, being provided with the shouldered, cam-projection 21. The stationary cams 19 are set upon the respective bushings 18, so as to place the projections 21 considerably to one side of a vertical plane cutting the axes of the two shafts 14 and 17, 50 and so as to be directly opposite each other in a plane parallel with the said plane cutting the axes of said shafts. These cam-projections 21 successively operate upon the plaiting blades of the respective sets to cause 55 alternative action thereof, as will be presently described.

Adjacent the cam 19, a collar 22 is splined or keyed, as at 23, upon the shaft 14, said collar being provided with a plurality of circumferentially arranged bearings 24 for the journals 25 of the plaiting blades 26. The journals 25 are each extended beyond the collar 22 and reduced, as at 27, and each journal has fixed thereon a tappet 28 for engagement with the stationary cam 19. Each

of said tappets is formed with a flat portion 29 adapted to bear upon the concentric circumference of the cam 19, and with an angular face-portion 30 adapted to engage the projection 21 of said cam. Owing to the compact arrangement and the great number of plaiting blades, each set has the tappets 28 arranged alternately at opposite ends, thus producing the construction clearly shown in Fig. 3, wherein the journal 25 of one plaiting blade is devoid of a tappet at the end viewed, while two adjacent blade-journals are provided with such tappets. This alternate arrangement produces great compactness and admits of a maximum number of blades being journaled in the collars 22. The tappets are keyed to the journals 27, so as to be readily removable and prevented from having rotary movement on the journals, this also providing a strong construction for imparting positive movement to the plaiting blades. The coöperative engagement of the concentric circumference of the cams 19 and flat portions 29 of the tappets is such as to hold the tappets, and, consequently, the plaiting blades, in fixed position after passing the cam-projection 21. This will be readily understood upon viewing Fig. 3. It will now be seen that the shafts 14 and 17, respectively, carry collars 22 at their opposite ends, and that each of the said collars has journaled therein a plurality of oscillating or independently movable plaiting blades 26. The shaft 14 and the two collars 22 thereon, and the complementary shaft 17 carrying the two collars 22 constitute blade-carriers, which rotate and, consequently, cause the plaiting blades to revolve around an axis, the blades at the same time having independent oscillatory motion relatively to each other and to the carriers.

The form of the plaiting blades, as shown in the drawings, is important for two reasons: (1) to provide a means by which, during the formation of a crease, the latter may be made sharp without cracking or injuring the fiber of the material at the fold, and (2) to provide against crushing the fiber of the material between the blades intermediate the folds. It will be seen, Fig. 4, that the folding edge 32 of one blade will enter the angle between the concentric portions of two adjacent blades and that, between the folding edges of interacting and coöperating blades, the material to be plaited will have no objectionable friction, pressure or crushing strain imposed thereon, since the surfaces of adjacent plaiting blades, concaved as desired, will be substantially free from the material between folds. I have adopted this form of blade, not from necessity, but from economy of construction, and I desire it distinctly understood that my invention is not confined to this particular form of blade, as other forms

may be found to accomplish the same results. The importance of this particular form of blade, however, is added to in view of the fact that the material is neither 5 crushed, distorted, dragged, scraped nor otherwise injured in forming the plaits, regardless of the texture of the material. Moreover, the cam actuating mechanism described has the important functional advantage 10 of giving to the plaiting blades in succession and alternately a quick inward movement to engage the material at the proper predetermined distance from the edge of an adjacent coöperating blade just 15 before the material is moved in the direction of feed for plaiting purposes. Thus, little by little, the material is moved forwardly to make the plaits without abrasion, scraping, or undue stress upon the surface 20 thereof, and the plaits are made uniformly and evenly and without even fractional variation.

Viewing Figs. 1 and 3, it will be seen that the bushings 18, to which the cams 19 are fixed, are held in their bearings, from 25 both longitudinal and rotary movement, by means of screws 33 threaded into the bearing members 5 and having a reduced, smooth end 34, which enters an aperture 35 in the bushing. This provides a convenient and effective means for locating the bushings in the bearings and holding the same, and the cams carried thereby, from movement. Moreover, it provides for the proper relative 30 disposition of the other cams for co-operative action upon the tappets 28 of the plaiting blades.

When it is desired to plait material of considerable width, it is necessary to provide 40 a machine of considerable length having very long plaiting blades, and, in order to support the said plaiting blades intermediate their journals 25, I have provided, see Figs. 1 and 4, a plurality of bearing members 36 in the form of grooved or corrugated collars splined upon the respective shafts 14 and 17, as at 37, said members 36 being provided peripherally with the semi-circular grooves 38, in which the concentric 45 portions 31 of the plaiting blades rest and oscillate. Any number of these bearing members may be secured to the shafts 14 and 17 between their ends, according to requirements or necessities of the machine. 50 By this means the blades are thoroughly braced between their ends, strain is removed from their journals, and quietude in action is provided.

In order to support the material to be 60 plaited conveniently to be entered between the plaiting blades, and to guide material of varying widths, uprights 39 are erected upon the bed 1 in any suitable position, at the rear of the plaiting blades, in the upper ends of which is journaled the shaft 40 of

the spool, carrying the bolt of material 41; and, to guide the support and guide the material between the spool and plaiting mechanism, any suitable guiding means is employed, the same being shown in Figs. 1 and 70 2 as consisting of uprights 42, provided at their upper ends with guiding flanges 43 and at their lower ends being each provided with a foot 44, having on its bottom a rib 45 adapted to slide in a correspondingly 75 formed groove 46 in the surface of the bed 1, said groove being centrally slotted, as at 47, through the bed to receive a screw-threaded bolt 48, the upper end of which is threaded into the foot 44, and the head 80 end of which engages a washer 49 to clamp the same against the base and thus hold the upright 42 in adjusted position. These guiding devices may be adjusted transversely of the bed relatively to each other, 85 so as to accommodate varying widths of materials which it may be desired to crimp. To support the plaited material at the front of the machine as it leaves the plaiting-blades, a tray or table 50 is provided which 90 may be supported in any suitable manner upon the bed 1, the same being shown, in Figs. 1 and 2 as supported by uprights 51 bolted to the bed. This table may be of any suitable form, being shown as curved 95 for the purpose of causing the plaited end 52 of the material to readily descend and pass away from the plaiting blades, under the feeding action of the latter, into any suitable receiver which may be provided for 100 the purpose.

In order to provide means by which the plaiting blades can operate upon varying thicknesses of material passed between them, without injuring the same when set for a 105 given thickness of material, I have provided the upper bearings for the shaft 17 with means for adjusting the same vertically upon the fixture 3. The means are shown in Figs. 1 and 2 and therein it will be seen that 110 said upper bearings are made in two parts 5 and 5^a, each provided on opposite sides of the bearing for the shaft 17 with slots 53, through which pass the bolts 54 threaded into the fixture 3. By this means the bearing members 5 and 5^a can be shifted vertically; and, to hold the position of adjustment, I have provided a screw-threaded sleeve 55 threaded into an extension 56 at the upper end of the fixture 3, which may be 115 set to engage the top of the bearing member 5^a to regulate its position. Passing through the sleeve 55 is a smooth bodied bolt 57, the lower end of which is threaded into the upper end of the bearing member 5^a, a 120 check-nut 58 being set, if desired, upon the upper end of the sleeve 55. By this means the bearings 5 and 5^a can be adjusted and firmly held in position, so as to regulate the interaction of the upper and lower set of 125 130

4
plaighting blades, thus providing means by which the fold or crease in the material may be made more or less sharp, and also providing means whereby the blades can properly fold, plait or crimp the material, regardless of its thickness.

From the foregoing description, it will be seen that I have provided a high speed plaighting apparatus of rotary form capable of plaighting any kind of flexible material and simultaneously feeding the same through the machine; and that, in performing the functions noted, the material is not marred or injured in any way and no objectionable strain is placed thereon. Consequently, the most delicate material, as well as strong and tenacious materials, can be operated upon and properly plaighted. Moreover, I have provided a mechanism which is capable of being extensively varied in size so as to adapt it to perform its functions upon materials of varying widths. On the other hand, it will be understood that material of a predetermined maximum width can be manipulated, as well as any narrower width to a predetermined minimum. Moreover, it will be understood that the operation of the plaighting blades, under control of the cams, can be made to perform their functions in predetermined manner, according to the form of the cams and their setting or location in the machine. These and other features which have been more or less stressed in the detail description are the important parts of my invention, as hereinafter claimed.

Having thus described my invention, what I claim and desire to secure by Letters Patent is:

40 1. A plaighting machine having a plurality of bodily rotating and relatively oscillating plaighting blades.

2. A plaighting machine having a plurality of sets of interacting plaighting blades, and means for bodily rotating the said sets relatively, and means for relatively oscillating said blades during their rotary movements.

3. A plaighting machine having, in combination, a carrier, means for rotating the same, a plurality of plaighting blades journaled in the carrier, and means for oscillating the same.

4. A plaighting machine having, in combination, a carrier, a plaighting blade journaled in said carrier, means for rotating the carrier, and means for giving to the blade movements independently of the carrier.

5. A plaighting machine having, in combination, a carrier, a plaighting blade journaled therein, means for rotating the carrier, and a cam mechanism for oscillating the plaighting blade.

6. A plaighting machine having, in combination, a carrier, means for rotating the same, a plaighting blade journaled in the car-

rier, and means for oscillating the plaighting blade comprising a fixed cam and a tappet coöperating therewith and with the blade.

7. A plaighting machine having, in combination, a plurality of plaighting blade carriers, 70 a plurality of plaighting blades journaled for independent movement in the carriers, means for rotating the carriers, means for oscillating the blades, the latter means including a fixed cam common to the blades 75 of each carrier, and tappets carried by the blades of each carrier for coöperation with said common cam.

8. A plaighting blade for plaighting machines substantially V-shaped in cross-section at its 80 executive side and having its angularly arranged sides concaved from vertex to base of the blade.

9. A plaighting blade for plaighting machines having its base in cross-section substantially 85 concentric with its longitudinal axis, and its executive side formed in cross-section as an acute-angle, the sides of which angle are tangential to the arc of the base.

10. A carrier for plaighting blades consisting of a driving-shaft, a pair of collars carried thereby, said collars having journal bearings therein, and plaighting blades journaled in said bearings. 90

11. A carrier for plaighting blades comprising 95 a rotary shaft, a plurality of collars carried adjacent opposite ends of said shaft, said collars being provided with a plurality of circumferentially arranged bearings, and a plurality of plaighting blades journaled in 100 said bearings.

12. A carrier for plaighting blades comprising a driving-shaft, a pair of collars fixed thereto having a plurality of bearings, a plurality of plaighting blades journaled in said 105 bearings, and means intermediate the bearings fixed to the shaft for sustaining the plaighting blades.

13. A plaighting machine having, in combination, a plurality of sets of interacting 110 plaighting and feeding blades, means for rotating the sets of blades relatively, means for giving to the plaighting blades successively, during each rotation, independent movements to feed in and press the material, 115 the blades of each set performing this function successively and alternately.

14. A plaighting machine having, in combination, a plaighting blade carrier, a shaft for said carrier, journal bearings for said shaft, 120 a plurality of plaighting blades journaled in said carrier, and supports intermediate the shaft bearings for sustaining the plaighting blades.

15. A plaighting machine comprising a bed, 125 bearings erected thereon, shafts journaled in the bearings, other bearings erected on the bed, a driving-shaft journaled therein carrying a worm, a worm-wheel carried by one of the first named shafts meshing with 130

the worm, and gearing between the said first named shafts for driving the latter, and plaiting mechanism carried by the latter shafts, substantially as described.

5 16. A plaiting machine comprising a plurality of interacting blades, means for supporting the blades, means for actuating the blades, and stationary guard-plates arranged in front of, and behind, certain of the blades
10 to prevent interference therewith.

17. A plaiting machine comprising a bed,

driving means mounted thereon, plaiting means, connections between the plaiting means, and driving means for actuating the plaiting means, a support for the material 15 in rear of the plaiting means, a support for the plaited material in front of the plaiting means, and adjustable guiding means for the material between the material-support and the plaiting means.

ROBERT G. CLARK.
